CLAIM

The ornamental design for a multi-function modulator and adapter, as shown and described.

DESCRIPTION

FIG. 1 is a front view of the multi-function modulator and adapter showing my design.

FIG. 2 is a rear view of the multi-function modulator and adapter of FIG. 1.

FIG. 3 is a right view of the multi-function modulator and adapter of FIG. 1.

FIG. 4 is a left view of the multi-function modulator and adapter of FIG. 1.

FIG. 5 is a top view of the multi-function modulator and adapter of FIG. 1; and,

FIG. 6 is a bottom view of the multi-function modulator and adapter of FIG. 1.

The broken lines showing are for illustrative purposes only and form no part of the claimed design.
